 Gwendoline Bruneau

(57) **CLAIM**

The ornamental design for a snow blower as shown and described.

DESCRIPTION

FIG. 1 is a perspective front view of the snow blower showing our new design;
 FIG. 2 is a front view of the snow blower;
 FIG. 3 is a rear view of the snow blower;
 FIG. 4 a first side of the snow blower;
 FIG. 5 is a second side view of the snow blower;
 FIG. 6 is top view of the snow blower; and,
 FIG. 7 is a bottom view of the snow blower.
 The broken line showing of the snow blower forms no part thereof.

1 Claim, 7 Drawing Sheets
